FREQUENCY SHIFT SIGNALING SYSTEM

Hallan E. Goldstine, Port Jefferson, N. Y., assignor to Radio Corporation of America, a corporation of Delaware

Application January 29, 1946, Serial No. 644,147

11 Claims. (Cl. 178—66)

1

This application discloses an improved method of and means for producing telegraphy signals or facsimile signals of the frequency shift type, or of the on-off type or telephony signals.

Frequency shift signalling systems are known in the prior art and the nature of these signals and known method of producing the same will not be discussed in detail herein. Frequency shift signals comprise two currents of different frequency alternatively usable. The shifting from one current to the other current is usually in accordance with intelligence represented by code. The current frequencies differ by several hundred cycles, and one may represent "mark" and the other "space" when telegraphy signals are being sent. When facsimile signals are involved one frequency may represent black or white. The character of telegraphy or facsimile systems of the on-off or amplitude modulation type are well known, as is the character of amplitude modulation telephony signals, and the same will not be described herein.

In frequency shift systems, as stated above, current is shifted from one frequency to the other in accordance with signals and this current or the same impressed on carrier current is transmitted. Obviously, in view of the already crowded condition of the radio frequency spectrum it is of considerable importance to have a system of this type wherein the mean or average or center frequency can be maintained constant, so that the frequency shifted current will not deviate from its assigned band in the frequency spectrum. An object of my invention is to provide an improved system wherein the center frequency is fixed. In my improved system this is accomplished by modulating an unstable oscillator from a first frequency to a second frequency and using the oscillator's output to modulate a crystal controlled oscillator of fixed frequency. The sum or difference side band is then selected for use at the fundamental frequency or a harmonic thereof.

My frequency shift means is to comprise a unit for use in new or existing transmitter systems. These transmitter systems may have or may be provided with crystal oscillators supplying the carrier current of fixed frequency used in providing frequency shifted side band energy of fixed center frequency. The modulated oscillator also must have the proper stable center frequency about which it is shifted to provide the final desired output frequency which may be harmonically related to the selected side band frequency which in the embodiment described is

2

the sum of the crystal frequency and the modulated oscillator frequency. A further object of my invention is to provide means for tuning the modulated oscillator to the exact desired center frequency without putting the transmitter on the air. This permits adjustment of the frequency shift unit in the laboratory and is accomplished by supplying a crystal controlled monitor oscillator of a frequency equal to the desired center frequency of the modulated oscillator and arranging the circuits so that the modulated oscillator frequency may be compared with and brought into synchronism with the crystal controlled oscillator frequency. This crystal controlled monitoring oscillator is also made use of as the modulated oscillator when amplitude keying or amplitude modulated telephony signals are to be generated.

Many telephony systems today make use of a tone keyed in accordance with intelligence. The tone is rectified to provide voltage having a direct current component varying between zero potential and a negative value, say minus 180 volts. The so varying direct current potential is then used to key the telephony system. My frequency shift unit is so arranged that it may be controlled by the output of these existing keyed tone converters. However, the output of the keyers supplying the tone for conversion is subject to variations due to variations in power supply voltage. This results in variations in the potential at the converter output. Since this tone converter output varies between about zero and a negative value signal limiting is inherent in the positive direction. The direct current varying potential in said prior systems is for use in amplitude keying and in such use signal limiting in the negative direction is not so important and is provided in the system. In my system, however, this direct current potential is to control a reactance tube modulating an oscillator and it is important that the signalling be also limited in the negative direction. A further object of my invention is to provide means which in cooperation with the existing keyed tone converters accomplishes signal limiting in both directions of the frequency shift operation. In accordance with my invention these variations are removed by provision of a gas discharge voltage regulator tube shunting the keyed tone converter output which is also in effect the reactance tube control input.

In on-off telephony systems the transmitted wave by necessity covers a considerable frequency band since the keying on and off of the carrier

current sets up numerous side frequencies. Where frequency shift signals are used considerable band width reduction is obtained. This is of considerable advantage and an object of my improved system is further reduction of the band width occupied by the frequency shifted currents. This is accomplished by supplying a low pass pi-section filter between the keyed tone converter and the reactance tube input. This filter shapes the signal wave and controls the rate of build-up of the keying characteristics and reduces the sideband spread and thereby utilizes less band width for the same keying speed and thus provides a reduction of adjacent sideband interference.

The extent of swing of the reactance tube modulated oscillator depends upon the variation of current through the reactance tube and this in turn depends upon the potential on the reactance tube grid. In my improved system the keying unit is to supply transmitters operating at the fundamental frequency or at various multiples thereof. The frequency shift at the modulated oscillator is then related integrally to the desired total frequency shift at the output. If the total swing is to be the same or substantially the same when the multiplication factor is changed the swing at the modulated oscillator must be reduced. An object of my invention is to provide simple and improved means for changing the total swing at the modulated oscillator an exact and known amount when the multiplication factor is changed. This means comprises an attenuation network which may be included in the circuit between the keyed tone converter and the reactance tube input to reduce the frequency shift swing.

When it is desired to change the extent of frequency swing or shift in systems of this nature the voltage applied to the reactance tube is varied more or less negative relative to zero. This not only changes the swing but may also change the center frequency. A further object of my invention is to provide improved means for recalibrating the modulated oscillator. In my system the arrangement is such that in the space condition the reactance tube is biased to be fully conductive so that the modulated oscillator supplies output of lowest frequency. In the mark condition the reactance tube is least conductive and supplies oscillations of a higher frequency representing mark. In order to facilitate centering of the oscillator frequency I provide a potentiometer arrangement such that half of the steady mark voltage may be applied to the reactance tube while its output frequency is being compared with the monitoring crystal oscillator frequency and the modulated oscillator is tuned to provide zero beat, as indicated by meter or other means, with the monitoring oscillator.

In an embodiment the center frequency is automatically corrected when the control potential applied to the reactance tube is changed. This is accomplished by simultaneously changing the reactance tube bias.

In an additional embodiment the center frequency is properly reset when the frequency swing is changed by changing the reactance in the controlled generator circuit.

In describing my invention in detail reference will be made to the attached drawings wherein Fig. 1 illustrates schematically and by block diagram, circuit element and circuit connections, a frequency shift keying unit arranged in ac-

cordance with my invention. Figs. 2 and 3 illustrate modifications of the arrangements of Fig. 1.

In the drawings, 10 is a tone generator and keyer which supplies keyed tone currents to a keyed tone rectifier or converter 16 from which direct current potentials varying between two values, one of which is fixed, are supplied to a reactance tube modulator 40. The supply circuit includes the voltage limiting tube 18, the frequency shift adjusting network including potentiometer 20 and the filter network 24. The attenuating network 28 may be included in the supply circuit. The reactance tube modulates an oscillator 60 which supplies excitation to an amplifier 76 of the cathode follower type, which in turn excites differentially a balanced modulator 100. The tubes 82 and 82' of the balanced modulator 100 are also excited cophasally by carrier current or voltage from a selected one of the two crystal controlled oscillator units 120 and 140. A side band resulting from the balanced modulation process is selected by tuned circuit 104 and fed to an amplifier stage 160 and from the amplifier stage to amplifiers and/or frequency multipliers 170 as desired. The crystal oscillator for monitoring purposes and for use in telephony and on-off telegraphy has been designated 200. The alternating current source for the heaters of the various tubes and for the rectifier supplying the direct current potentials and for the temperature regulating units have been omitted for the sake of simplicity. The direct current potential source, not shown, has its output coupled to voltage regulators 220 so that direct current potentials of constant amplitude are provided for certain of the tube electrodes in the modulator stage and modulated oscillator circuits and in the crystal controlled monitoring oscillator 200. A switching and metering arrangement for use in making the necessary adjustments and tuning operations is designated generally at 250.

The frequency shift modulation is carried out as follows. Keyed potentials filtered and modified and used as will be described hereinafter are applied to the control electrode 30 of a reactance tube 40 to vary the conductivity thereof. The reactance tube has its anode 34 and cathode 36 shunting a portion of tuned tank circuit 39 of the oscillation generator including one electron discharge system of tube 60. The oscillator per se is substantially conventional and will not be described in detail herein. It includes, however, inductance 41, a portion of which connects the grid and the anode of tube 60 in a regenerative circuit. This inductance is shunted by a plurality of tuning condensers 44, which are of temperature compensating type, and the entire inductance 41 is shunted also by a trimmer condenser C6 in series with the condenser C40, also used to tune the oscillator. The grid bias supply for the triode 60 includes a radio frequency choke inductance L2 and resistor R3. In the embodiment being described oscillator 60 operates at about 200 kc. The reactance tube has its output electrodes shunting a portion of the inductance 41 so that the reactance of the tube 40 is included in the tank circuit 39 and takes part in determining the frequency of operation of the oscillator. The reactance tube 40 is of a type well known in the prior art, having its anode 34 operating at a first radio frequency voltage by virtue of its connection to the tank circuit 39 and its control grid 30 operating at an R. F. voltage in quadrature phase relation to said anode voltage by virtue of the operation of the phase shifting

network including condenser C, resistance R₁ and inductance 27.

The amplifier tube system 70 has its control grid 71 coupled by condenser C8 to the anode of tube 60 to be excited by oscillatory energy developed in the generator including tube 60. The tube 70 is in a cathode follower circuit with a radio frequency choking inductance L₃ and resistor R₅ in its cathode return circuit. The cathode follower stage is used to keep the wave form 10 of the oscillator-amplifier stage reasonably clear of harmonics. Since the cathode follower has a large amount of degeneration, the cathode feedback will tend to maintain the grid-cathode voltage constant. This effect makes the amplifier 15 more linear. Moreover, the low impedance output of the cathode output keeps the R. F. voltage lower due to the low gain and helps prevent feedback effect on the oscillator.

The amplified oscillations are supplied from the radio frequency choking inductance L₃ by coupling condenser C5 to the primary winding 73 of a transformer T₁ having its secondary winding coupled by a tuned circuit 75 in pushpull relation to the first grid electrodes 80 and 80' of the two tubes 82 and 82' in the balanced modulator 100. The balanced modulator 100 also has the tube grids 80 and 80' excited in like phase by crystal controlled oscillations from tuned circuit 83, the inductance of which forms the secondary winding of tuned transformer T₂. The primary winding of the transformer T₂ is connected to the anode of the tube 119 of the high frequency crystal generator 120 and to the anode of the tube 139 of the high frequency crystal controlled oscillator 140. One or the other of these oscillators, here oscillator 120, is operative to supply oscillations of the fixed desired carrier wave frequency depending upon the position of selector switch S4. The energy is fed from the high frequency crystal oscillator through the transformer T₂. The secondary of T₂ is tuned to the crystal frequency and the energy is fed through condensers C10, C11 and C12 and C13 to the grids of tubes 82 and 82' in parallel. The resistors R₇ and R₈ are high impedance grid leaks and prevent the tube from drawing excessive grid current. The condensers C10, C11 and C12 and C13 tune the secondary winding of transformer T₁ to the low frequency (200 kc.) but offer a low impedance path for the oscillatory energy fed from the selected crystal oscillator through transformer T₂ and the harmonics of these oscillations.

The oscillators 120 and 140 are not being claimed herein and will not be described in detail. They are, however, very good stable oscillators in temperature controlled units so that the carrier oscillations supplied to the balanced modulator are of good strength and of substantially constant frequency.

The anodes of the two modulator tubes of the balanced modulator 100 are coupled differentially to a tuned tank circuit 104 the inductance of which forms the primary winding of a transformer T₃. This circuit 104 is tuned to pass a side band resulting from intermodulation of the oscillations from the oscillator tube 60 and from the selected crystal oscillator 120. The high frequency oscillations derived from the crystal, as known, are phase opposed in the tank circuit 104 and balance out. The low frequency oscillations supplied from the oscillator including tube 60 are tuned out and the tuned circuit 104 is adjusted to supply the upper or lower side band. In the embodiment illustrated, the upper side band is

used. The selected side band is supplied to the control grid 129 of an amplifier tube 130 and after amplification therein is impressed from the output tuned transformer T₄ on to a short line (jack J3 and pin contact P3) and thereby supplied to the amplifiers and frequency multipliers in the transmitter equipment 170. The frequency multipliers are assumed herein to have a multiplication factor of 4 or of 8.

The monitoring oscillator 200 comprises an electron discharge device 205 having its first two grids coupled in an oscillation generator circuit including a crystal X3. The tube includes an additional shielding electrode 207 which is grounded to shield the anode 209 from the oscillation generating circuits except through the coupling thereto by the electron stream within the tube. The anode of this oscillator tube is coupled to the primary winding 13 of the transformer T₁ under certain conditions and for certain purposes as will be described hereinafter. The anode of oscillator tube 205 is also coupled to the primary winding 73 of transformer T₁ to a positive source of direct current potential through the switch S3 in one of its positions when the crystal controlled monitoring oscillator 200 is put into use. This will be discussed in detail hereinafter in the statement of operation of the system.

At 250 I have shown a switching arrangement (which has been simplified and includes only a portion of the switching arrangement in the embodiment tested) used in regulating, adjusting and tuning the system. The milliammeter M₁ 30 may be connected in series with the cathode return circuit of the reactance tube 40, or with the cathode return circuit of the oscillation generator 60, or with the cathode return circuit of the amplifier tube 70, or in series with the cathode return circuit of the tubes of modulator 100, or in series with the direct current screen grid circuits of tubes 82 and 82', or with the grid circuit of the amplifier tube 130, or with the anode circuit of the tube 130, or with the resistances 45 R₁₉ and R₂₀ terminating the low pass filter 24 depending upon the positions of the switches 249 and 253.

While it is believed that my invention has been made clear to those versed in the art, the purpose and operation of essential and novel features thereof will now be described in detail. The keying voltage from the converter 16 is fed to the voltage regulator tube 18. As stated above, this voltage varies from zero in a negative direction, say to about -180 volts, but may vary more or less due to variations in the potential used on tubes in the tone generator and keyer 10. The voltage regulator tube 18 is so poled that when the negative potential at its electrode 17 exceeds a selected amount a limiting action takes place. In the embodiment described this tube is used to limit the negative swing of the keyed pulse to about -150 volts. The converter 16 does not have any limiter and if the power supply voltage therefor varies the keyer output varies and lets the power supply modulate the keying. The tube 18 eliminates this effect. The output of the tube 18 is connected to a resistor 19 in series with an adjustable part of the potentiometer resistor 20 and ground. The input voltage to the reactance tube 40 is adjusted by means of this potentiometer 20 and thus the total frequency shift may be set from any value between zero and some upper maximum value say, for example, 1200 cycles by 75 means of this adjustment. The frequency swing

is measured and the potentiometer 20 is calibrated to give the proper frequency shift for the correct potentiometer adjustment. This shift should not depart from the calibration unless the reactance tube 40 should change radically or depart from its normal characteristics. By using a monitor receiver and checking the beat note on mark and space keying, the frequency shift may be checked. In the embodiment being described the frequency shift is set at a total of 850 cycles. The output of the potentiometer 20 is fed to switch S2 which is used to include or exclude the resistive pad 28 in or from the input connections to the reactance tube 40. Whether or not this resistive pad 28 is included depends upon the amount of frequency shift to which the output is subjected in the multipliers 170. In the embodiment described, with a total frequency shift of 850 cycles output and a multiplication of 4, the reactance tube and oscillator is adjusted to produce a frequency shift of about 212.5 cycles total. If a frequency multiplication of 8 is used at 170 then obviously the frequency shift accomplished at the modulated oscillator 60 must be divided by 2, or be about 106 cycles total. With the resistor attenuating pad 28 out the adjustment is made such that the reactance tube 40 modulates the oscillator 60 through a range of 212.5 cycles total. Then the multipliers at 170 have a factor of 4. If the multipliers at 170 have a multiplication factor of 8 then the switch S2 is moved to its other position to include the network 28 in the input circuit of the reactance tube 40. The network 28 consists of a 6 db. pad and the attenuation is such as to reduce the maximum negative potential on the control electrode of the reactance tube 40 to reduce the total here to one-half its previous negative value so that the output total swing will remain essentially fixed at 850 cycles. Thus, once the potentiometer 20 has been set the same does not need to be reset for different multiplication factors unless the total output shift is changed from the assumed 850 cycles.

The output of the potentiometer 20 feeds directly or by pad 28 into a low pass filter 24 composed of condenser 23 and inductance 25, and a section of the condenser C3 (at the lower end of 27). These connections include the switch S3 in the position shown so that the voltage passed by the low pass filter is supplied to the inductance 27 and thence to the control grid 30 of the reactance tube 40. The filter 24, as stated hereinbefore, shapes the signal wave and controls the rate of buildup of the keying characters, thus narrowing the spread of the radio frequency side bands. The filter is terminated by resistors R19 and R20.

The switch S3 has three positions, one designated Frequency shift, another designated Frequency calibrate, and the third Phone. In the Frequency shift position it will be noted that the regulated direct current potential is supplied from the positive terminal of the source and through one of the voltage regulator tubes 220 by lead 31 to the screen grid 32, and by lead 33 to the anode 34 of the reactance tube 40, and simultaneously this regulated direct current voltage is supplied to the anode of the oscillator tube 60 and the anode of the amplifier tube 70. Then the frequency of the oscillations generated in oscillation generator tube 60 is swung by the keying voltage including the direct current component through a first range if switch S2 is in the position shown; or through a range half as

wide as said first range if the switch S2 is put in the other position. The plate and screen voltages are regulated by means of voltage regulator tubes V8 and V9. The 200 kc. oscillator including tube 60 is stabilized for ambient temperature variations and also for voltage variations. The other half of this tube, i. e., section 70, is used as an amplifier. The amplifier 70 is loosely coupled to the oscillator 60 through condenser C8 and the output is taken from the cathode impedance L3 through coupling condenser C5.

In the Calibrate position of switch S3, direct current voltages are supplied as described above and also by leads 35 to the anode and screen grid of the crystal controlled monitoring oscillator 200. In the Calibrate position then the direct current modulated oscillator 60, the amplifier 70, and the monitor crystal controlled oscillator 200 are all operating. However, in this position of the switch the control grid of the reactance tube 40 is connected by resistor R1 and inductor 27 to a point between resistors R19 and R20 so that only half of the keying voltage on steady mark (i. e., one-half of the highest negative voltage) is supplied to the reactance tube. If the tube 40 characteristic is about linear, now the frequency at which the oscillator 60 operates should be the desired center frequency, in the example given, 200 kc. To check this frequency the 200 kc. frequency shift oscillator is adjusted or tuned by means of trimmer condensers C3 and C40 if necessary to establish zero beat with the crystal oscillator 200. For this adjustment the transmitter need not be "on the air." The intensity of the current flow shown by the milliammeter M1, included by lead 89 and switches 249 and 253 in the cathode return circuits of the balance modulator tubes 82 and 82', indicates zero beat. This centers the carrier frequency of the frequency shift half way (if the reactance tube is linear) between mark and space frequency.

When the switches are in the position shown the resistor R19 and R20 at the terminal of low pass filter 24 are connected to ground through lead 27' and meter M1. Other switching means (for the sake of simplicity not shown) opens the ground connection to R19 and R20 at the point 28. The meter M1 may be connected in series with resistors R19 and R20 and ground to indicate the keying current flowing in R19 and R20, thus giving the keying voltage applied to the grid 30 of the resistance tube 40. In fact this may be used as an indication of frequency shift for setting the potentiometer 20, so that the frequency shift could be calibrated against keying current on mark condition.

The reactance simulated by tube 40 depends on the current therethrough. The current therethrough depends on the grid potential. In order to facilitate adjustment of the circuits to cause the tube to operate at the middle of the linear portion of its characteristic curve, its cathode may be connected to ground through lead 43 and switches 249 and 250 instead of directly as shown at 45. In the embodiment used additional switching means, not shown, opens the ground connection at 45 when the connections through lead 43 and switches 249 and 253 are completed to put the meter M1 in the cathode return circuit of the reactance tube 40. Now the adjustments at 20 can be made to get the desired maximum currents through the tube (observations made at M1) to get the desired re-

actance change and frequency swing. The additional switching means has been omitted in order to simplify the drawings. The cathodes 53 and 63 of tubes 60 and 70 are also arranged to be connected through meter M1 by leads 55 and 65 respectively, and switches 249 and 253. When so connected, the direct ground connections for these cathodes are broken at 57 and 67 by the switching means (not shown), described above, which is controlled simultaneously with switches 249 and 253. In the shown position of these switches, the ground connections for cathodes 53 and 63 are completed at 57 and 67.

Similar means including lead 89 between switches 249 and 253 and the cathodes of the balanced modulator tubes 82 and 82' and the switch (not shown) contact 84, and leads 103 and 105 between switches 249 and 253 and the screen grids of balanced modulator tubes 82 and 82' and the switch (not shown) contacts 107 and 109, and lead 111 between the grid 129 and switches 249 and 253, and switch (not shown) contact 115 and lead 147 between the anode and tuned circuit 153 and switches 249 and 253, and switch (not shown) contact 149 and lead 201 between the cathode of the monitor oscillator 200 and switches 249 and 253 and switch (not shown) contact 203 and lead 27' between the resistance R20 and the meters 249 and 253 and switch (not shown) contact 29, are provided for tuning and adjustment of the balanced modulator 100, the amplifier 160, the monitor oscillator 200, and for adjustment of the potentiometer 20 and 28.

On Phone position of switch S3 only the crystal controlled oscillator 200 is excited and the transmitter frequency control is supplied by this crystal oscillator and the crystal oscillator at 120 or 140. This position may be used if amplitude or amplitude keying is desired. The transmitters may be equipped with amplitude telephony or in some cases amplitude (on-off) keying may be desired. The amplitude keying is usually accomplished in a later stage by methods well known to the art. The amplitude telephony may be accomplished in the last (output stage) or one of the other stages of the transmitter.

When the extent of frequency swing is changed by say adjustment of potentiometer 20 or by including network 28 in the reactance tube input the center frequency of operation of the system is changed. In this respect it may be kept in mind that the minimum negative voltage (zero potential) applied to the input is fixed. To further improve systems of this type means for automatically centering the carrier frequency is provided.

Automatic centering of the carrier frequency may be accomplished if a bias voltage is applied to the reactance tube through a potentiometer which is mechanically coupled to frequency shift adjustment 20. When the frequency shift control is varied or when the selector switch (X4—X8) is changed the proper correcting voltage is applied to the grid of the reactance tube to keep the carrier essentially centered. In Fig. 2 I illustrate a method of applying a bias to the reactance tube control grid in the proper relation, to keep the carrier frequency essentially centered. In this embodiment reference numerals corresponding to those used in Fig. 1 are used in so far as possible. Resistors R100 and R101 of which R100 is a potentiometer ganged with potentiometer 20 have been added with R100 connected by switch S102 and part of source

300 to ground, or by way of source 300 to ground. The tap on R100 is connected by switch S103 to a point between resistances R102 and R103 or to a tap on R103. R102 and R103 are in series with R19. The contacts of S3 in the direct current supply circuits for the various tube electrodes etc., other than that used between the reactance tube and signal input, and the meter M1 connections by switches 249 and 253 have been omitted for the sake of simplicity.

When the switches are in the positions shown the grid circuit of tube 40 includes R1, 27, R19, R102 and all of R103 and also part of R103 shunted by an adjustable portion of R100 in series with R101 and source 300. The resistor R101 and variable resistor R100 are in series of a value sufficiently high, so that the current through R103 is independent of the value of R103. The potentiometer 20 is mechanically connected to R100 so that the bias is varied correctly as the frequency shift adjustment 20 is changed. As the frequency shift is made smaller, bias is applied to the reactance tube to recenter the carrier. Switch S102 is ganged with switch S2, so that when the input signal is twice (the pad 29 out), twice the normal bias is applied to the grid of the reactance tube. It is not necessary to have S103 as illustrated and this switch may be deleted from the drawing. Then the connection from R100 goes directly to resistor R103. However, if desired, switch S103 may be included (as shown) and be ganged with switch S2. Then switch S102 may be removed and source 300 included between R101 and ground.

Another method is to have a small trimmer condenser in parallel with C6 mechanically coupled to frequency shift adjustment 20, so arranged that when the frequency shift adjustment is changed the carrier is shifted to provide a fixed center frequency. A small fixed condenser may also be switched in and out of the circuit when switch S2 (X4—X8) is changed. This embodiment is illustrated in Fig. 3. When the potentiometer 20 is adjusted to change the frequency shift the condenser C106 in shunt to condenser C6 is adjusted to center the carrier frequency. When the switch S2 is thrown to the lower position to put the pad 28 in the input circuit the condenser C107 heretofore in shunt to condenser C6 is removed from the oscillator circuit to increase the oscillator frequency.

Another method is to use pushpull D. C. input signals, say plus for mark and minus for space. Pushpull reactance tubes may then be used and to center the carrier it is only necessary to remove the input signal and the reactance tubes are then at their normal carrier and the frequency shift for equal mark and space voltages. The pushpull reactance tubes also make the frequency shift system less susceptible to power supply variations in the unit.

In operating the system the procedure described above and the following procedure may be followed.

After the set is turned on the operator will of course know and select which of the high frequency crystal controlled oscillators 120 or 140 he is to use. This selection is made by use of switch S4. Then the switch S3 is placed on the frequency shift position and the crystal tuning dial on condenser C15 in circuit 83 is set at the proper position or approximately there. This circuit is tuned for maximum modulation as denoted by maximum cathode or screen grid current on the meter M1, switches 249 and 253 being

turned to the proper position. The modulator tuning dial on the condenser C19 of circuit 104 is then placed at the proper setting. Curves supplied with the unit may be used to approximately determine this setting and the dial is then slightly tuned to obtain maximum output which may be denoted by the grid current in the tube 130, its grid return circuit then being connected by switches 249 and 253 through the meter M1. This circuit, which in the embodiment described is tuned to the upper side band, must be carefully tuned and is quite sharp. The output tuning condenser C22 is then properly set and in doing so the anode current of tube 130 as indicated on the meter M1 may be observed in making this adjustment. The input keying signal is then placed on mark condition to apply a steady potential equivalent to mark potential across the resistor 20. The frequency shift adjustment by potentiometer 20 is then made to give the desired frequency shift as indicated by current through the meter M1 when the same is connected in series with the resistors R19 and R20. The switch S2 is then set in the X4 or X8 position, X4 indicating that a multiplication factor of 4 is used, and X8 indicating that a multiplication factor of 8 is used. The control switch S3 is now placed in the Calibrate position and by adjustment of the condenser C6 and/or C40 the oscillators 60 and 200 are brought into zero beat, this condition being indicated by slow variation of current in the meter M1 when the same is in series in the return circuit of the modulator tubes 82 and 82'. Now the switch S3 is put on the frequency shift position and the steady mark signal potential is removed and keying signal put on.

What is claimed is:

1. In a signalling system, in combination, an alternating current circuit means for causing oscillatory energy to flow in said circuit, a reactance tube having electrodes in shunt to at least a part of said circuit to tune the same, said reactance tube having a biased control grid, the magnitude of the energy on which controls its reactive effect, connections to said control grid for applying pulse energy to said control grid the magnitude of which is keyed between first and second values in accordance with signals to vary the tuning of the circuit between two limits symmetrically related to a center frequency, an adjustable resistance in said connections for changing the extent of the separation between said first and second values of the pulse energy to thereby change the extent of variation of the said tuning of said circuit, and means for simultaneously recentering the tuning of said circuit at said center frequency when the extent of separation between said two values of the pulse energy is changed.

2. A system as recited in claim 1 wherein said last means is a second reactance element in said circuit.

3. A system as recited in claim 1 wherein said last means is a controllable bias source for said reactance tube.

4. In a signalling system, in combination, an oscillation generator circuit wherein oscillatory energy appears, a reactance tube having electrodes in shunt to at least a part of the generator circuit to tune the same, said reactance tube having a biased control electrode the potential on which controls its reactive effect, connections to said control electrode for applying pulse energy to said control electrode which varies from a first value through a mean value to a third value in accordance with signals to shift the

frequency of the oscillatory energy with respect to a mean or average frequency, means for adjusting the value of said applied pulse energy to thereby change the extent of said frequency shift, means for recentering the mean or average frequency of operation of said oscillation generator when the value of the applied pulse energy is changed comprising an adjustable resistance in the bias circuit for said control electrode, and common control means for said last two means.

5. In a signalling system, in combination, an oscillation generator circuit wherein oscillatory energy appears, a reactance tube having electrodes in shunt to at least a part of the generator circuit to tune the same, said reactance tube having a biased control grid, the magnitude of the energy on which controls its reactive effect, connections to said control electrode for applying pulse energy to said electrode the magnitude of which is keyed between first and second values in accordance with signals to vary the frequency of the generated oscillatory energy with respect to a selected value, an adjustable resistance for changing the magnitude of the pulse energy to thereby change the extent of variation of the oscillatory energy with respect to said selected value, means for recentering the frequency of operation of said oscillation generator when the magnitude of the pulse energy is changed comprising an adjustable resistance in the bias circuit of said control grid, and a common control for said adjustable resistances.

6. In a signalling system, in combination, an oscillation generator circuit wherein oscillatory energy appears, a reactance tube having electrodes in shunt to at least a part of the generator circuit to tune the same and control the generator frequency, said reactance tube having a biased control electrode the potential on which controls its reactive effect, connections to said control electrode for applying pulse energy to said control electrode which varies from a first value through a mean value to a third value in accordance with signals to shift the frequency of the oscillatory energy with respect to a mean or average frequency, means for adjusting the value of said applied pulse energy to thereby change the extent of said frequency shift, means for recentering the mean frequency of operation of said oscillation generator when the value of the applied pulse energy is changed comprising an adjustable reactance in said oscillation generator circuit, and common control means for said last two means.

7. In a signalling system, in combination, a circuit wherein oscillatory energy flows, a reactance tube having input electrodes and having output electrodes coupled to said circuit for controlling the tuning thereof and thereby controlling the timing of the said oscillatory energy, a source of direct current potential which varies between two values connected to the input electrodes of said tube to vary the current therethrough and thereby vary the timing of the oscillatory energy between two values, frequency increasing means coupled to said circuit for increasing the range between said last named two values, direct current and alternating current potential attenuating means, and switching means arranged to include said last named means in the connection between said source of direct current potential and the input electrodes of said reactance tube when the multiplication factor of the frequency increasing means is made larger.

8. In a signalling system, in combination, a circuit wherein oscillatory energy flows, a reactance tube having input electrodes and having output electrodes coupled to said circuit for controlling the tuning thereof and thereby controlling the timing of the said oscillatory energy, a source of direct current potential which varies between two values, one of which is fixed and the other of which may vary in an undesired manner, coupled to electrodes of said tube to vary the current therethrough and thereby vary the timing of the oscillatory energy between two values, a voltage regulator tube in shunt to said source and poled so as to limit variations of said other potential so that the timing of said oscillatory energy is varied through a fixed range, frequency converting and frequency multiplying means coupled to said circuit for multiplying the range through which said oscillatory energy is varied, a direct current potential attenuator, and a switch to include said attenuator in the connection between said source of direct current potential and the input electrodes of said reactance tube when the multiplication factor of the frequency increasing means is made larger.

9. In a signalling system, in combination, a circuit wherein oscillatory energy flows, a reactance tube having input electrodes and having output electrodes coupled to said circuit for controlling the tuning thereof and thereby controlling the timing of the said oscillatory energy, a source of direct current potential which varies between two values, one of which is fixed, coupled to the input electrodes of said tube to vary the current therethrough and thereby vary the timing of the oscillatory energy between two values, a voltage limiter coupled across said source and poled to fix the other value between which said potential varies, to thereby fix said two values between which the oscillatory energy is timing modulated, a low pass filter in the coupling between said source and the input electrodes of the reactance tube to reduce side frequencies produced by variations of said potential, frequency increasing means coupled to said circuit for increasing the frequency range through which the oscillatory energy is modulated, a control potential attenuator, and means to introduce said attenuator in the connection between said source of direct current potential and the input electrodes of said reactance tube when the multiplication factor of the frequency increasing means is made larger.

10. In a signalling system, an oscillation gener-

ating circuit, a reactance tube having output electrodes associated therewith for controlling the frequency thereof, a source of modulating potentials of varying value coupled to the input electrodes of said reactance tube to modulate the frequency of said circuit, means for multiplying the frequency of the output of the said modulated circuit, a potential attenuator, and a switch for introducing said potential attenuator in the connection between said source of modulating potentials and the input of said reactance tube when the multiplication factor is changed.

11. In a signalling system, in combination, an oscillation generator circuit wherein oscillatory energy appears, a reactance tube having electrodes in shunt to at least a part of said circuit to tune the same and control the generator frequency, said reactance tube having a control grid the potential on which controls its reactive effect, connections to said control grid for applying pulse energy to said control grid the magnitude of which varies from a first to a second value in accordance with signals to vary the effective reactance and the frequency of the oscillatory energy, and means for centering the frequency of operation of said oscillation generator comprising a crystal controlled oscillator operating at the desired center frequency, means for applying a potential equal to one-half said second value to said control grid of said reactance tube, and means for then adjusting the frequency of the modulated oscillation generator until it equals the frequency of the crystal controlled oscillator.
